UNITED STATES PATENT OFFICE

GEORGE W. ORTH, OF PHILADELPHIA, PENNSYLVANIA

BUILDING FLASHING

Application filed March 27, 1931. Serial No. 525,678.

This invention relates to building flashing and has special reference to flashing for use either as a bonding material between courses of masonry, or as a water-proofing material beneath copings and the like.

One of the objects of this invention is to provide a flashing which will be of minimum thickness while still providing maximum bonding properties.

Another object of the invention is to provide an efficient flashing which is simple in construction and which can be cheaply manufactured.

According to the invention, the flashing 10 comprises a plate or holding member and collapsible members attached thereto. These collapsible members may be on one or both sides of the plate, and the plate itself may be constructed of metal or waterproof material, and the collapsible members may, if desired, be woven with the plate.

The drawings illustrate embodiments of the invention and the views therein are as follows:

Figure 1 is a top plan view of one form of my improved flashing,

Figure 2 is a side view of the same,

Figure 3 shows a section of a building construction with my improved flashing incorporated between two courses of masonry,

Figure 4 is a fragmentary longitudinal sectional view of a modified form of my flashing,

Figure 5 is a fragmentary side elevation of another form of my improved flashing, and

Figure 6 is another modified form showing the use of a waterproof plate which may be either fibrous or metal.

Referring to Figure 1, the plate 7 may be 40 of metal, if desired, and provided with longitudinally extending parallel wires 8, the wires being bent into a series of elongated U-shaped sections 9, and the legs of the sections abutting the plate 7 at 11.

In the form shown in Figure 2, it is in-

tended that the points 11 shall be spot-welded so as to attach them securely to the plate 7, and while I have shown the wires 8 on both sides of the plate 7, I do not limit myself to this construction, as I may only use the wires 50 on one side thereof.

At the ends of the plate 7, shown in Figure 2, I have shown, in dotted lines, extensions in the form of hooks 12 for interlocking a plurality of the plates 7.

The dimension α in Figure 2 may vary according to the will of the manufacturer, and the gauge of the wire 8 is intended to be such that when placed between two courses of masonry, as shown in Figure 3, the U-shaped sections 9 will collapse and approach the plate 7 so as to embed themselves firmly in the mortar 13, and while providing a substantial bond between the two courses of masonry, be not prohibitive in thickness.

Various types of flashing on the market today are excessive in thickness and the holding members thereon will press through the entire body of mortar and engage the masonry courses, whereas the efficient flashing is 70 that which embeds itself in the mortar and permits of a substantially small distance between the masonry courses.

Figure 4 shows a plate 14 which may be of metal or other material, and which has 75 holes 16 at various intervals throughout the same. There is threaded through these holes, both up and down, wires 17 which, when the flashing is placed between two courses of masonry, will not only bend to assume the 80 position shown by the flashing in Figure 3, but will be slightly assisted in this operation by pivoting to some extent on the point 18.

Figure 5 shows a flashing substantially the same as Figure 2, except that the wires are held to the plate 7 by the rivets 19.

Figure 6 shows a fibrous plate 21 with the wires 17 punched or pushed through the same. This plate 21 may be of metal and adapted for the carrying of the wires 17 and 90

for the particular utility of waterproofing.

My invention embraces the use of ordinary wide gauge wire netting, such as chicken wire which may be attached to the waterproofing plate in any desired manner, and the major portion of the wires thereof will be extended from said plate so that when placed between two courses of masonry, the wires will embed themselves in the mortar and be collapsed as explained.

Of course, the flashing illustrated may be modified and changed in various ways without departing from the invention herein set forth and hereafter claimed.

15. The invention is hereby claimed as follows:
  1. A building flashing comprising a substantially plane plate, and longitudinally extending parallel holding members attached thereto and collapsible toward said plate.
  20. 2. A building flashing comprising a substantially plane plate, and longitudinally extending holding members attached to each side thereof and collapsible toward said plate.
  25. 3. A building flashing comprising a substantially plane plate, and wires attached thereto and bent so that collapsible portions thereof are spaced from said plate.
  30. 4. A building flashing comprising a substantially plane plate, and longitudinally extending parallel wires attached thereto and bent so that collapsible portions thereof are spaced from said plate.
  35. 5. A building flashing comprising a plate having wires bent into a series of elongated U sections, and legs of said sections being attached to and spacing the intermediate parts away from said plate.
  40. 6. A building flashing comprising a plate having longitudinally extending wires bent into a series of elongated U sections, the legs of said sections being attached to and spacing the intermediate points away from said plate.
  45. 7. A building flashing comprising a substantially plane plate, and collapsible members extending therethrough at spaced points, the intermediate parts thereof being spaced from said plate.
  50. 8. A building flashing comprising a substantially plane flexible plate, and collapsible members extending therethrough at spaced points, the intermediate parts thereof being spaced from said plate.
  55. 9. A building flashing comprising a substantially plane plate, and wires bent and threaded through from side to side of the same.
  60. 10. A building flashing comprising a substantially plane waterproof plate, and wires bent and threaded through from side to side of the same.
  65. 11. A building flashing comprising a substantially plane plate, and wires bent and threaded through from side to side of the

same with portions of said wires spaced from said plate.

12. A building flashing comprising a plate, wires connected at spots along their length to said plate, and having their major portions spaced from said plate, said portions being of a nature adapting them to be bent toward said plate when placed between courses of masonry.

In testimony whereof I have signed my name to this specification.

GEORGE W. ORTH.
